CLAIM

The ornamental design for an itch relief device as shown and described.

DESCRIPTION

Figure 1.1 is a perspective view of an itch relief device;

Figure 1.2 back perspective view thereof;

Figure 1.3 front view thereof;

Figure 1.4 back view thereof;

Figure 1.5 left view thereof;

Figure 1.6 right view thereof;

Figure 1.7 top view; and

Figure 1.8 bottom view.

The broken lines shown in the figures illustrate portions of the itch relief device that forms no part of the claimed design.
